CLAIM

The ornamental design for a lighted drain cartridge, as shown and described.

DESCRIPTION

FIG. 1 is a front perspective view of a lighted drain cartridge.

FIG. 2 is a side perspective view of a lighted drain cartridge.

FIG. 3 is another side perspective view of a lighted drain cartridge.

FIG. 4 is a top perspective view of a lighted drain cartridge.

FIG. 5 is a bottom perspective view of a lighted drain cartridge; and,

FIG. 6 is a top perspective view of a drain cartridge having light emanating therefrom.

The broken lines depicting an outline of a drain and objects around the drain cartridge form no part of the claimed design.

The dominant feature of my design resides in the light emitted from a portion of an upper surface of the cartridge that has been line shaded for color.
